UNITED STATES PATENT OFFICE.

ORAN W. SEELY, OF SYRACUSE, NEW YORK.

IMPROVEMENT IN DEVICES FOR OPERATING CHURNS.

Specification forming part of Letters Patent No. **38,013**, dated March 24, 1863.

To all whom it may concern:

Be it known that I, ORAN W. SEELY, of Syracuse, county of Onondaga, and State of New York, have invented a certain new and useful Improvement in Churns; and I do hereby declare that the following is a full, clear, and exact description of the same, reference being had to the accompanying drawing, and to the letters of reference thereon.

My invention relates to an improvement in the means for operating the dash-churn; and it consists in the employment of a vertically-reciprocating connecting-rod, the upper end of which is connected to the churn-dasher and the lower end of which is connected to a balanced rocking lever, arranged and operating as will be hereinafter more fully described.

In the drawing, A represents a base or platform, to which are secured in any suitable manner four stout uprights, B B', which are connected by longitudinal beams C C', and cross-ties D and D'. The upper and lower longitudinal beams are further strengthened by uprights E midway of their length.

F represents the main or driving shaft, resting on and properly journaled in the longitudinal beams C, on one end of which shaft is secured the crank-handle for driving the same. The other end of this shaft is provided with the driving spur-wheel G, which meshes with and drives pinion H on shaft I, which is journaled in uprights E E and provided with the fly-wheel K on its outer end, and midway of its length and of the width of the frame and platform, with a short crank, L.

N represents a horizontal balanced lever connected to the rock-shaft O, which is journaled in the lower longitudinal beams, C'. Motion is imparted to said balanced lever and rock-shaft by crank L on shaft I, through connecting-rod M. The uprights B', it will be seen from the drawing, extend for about one-third of their length above the longitudinal beams C, being connected at their upper ends by the cross-tie D'. This cross-tie is perforated midway of its length between the uprights,

and forms a fixed guide to the vertically-reciprocating connecting rod or slide a, which has its lower end connected to one end of balanced lever N. The upper end of this rod is bent to a right angle, or thereabout, as at a', and is forked, as shown at a'', to embrace the handle of the dasher e e' e'' of churn P, said churn resting on an extension, A', of the platform A. This churn P may be of the usual form and construction, except that I find it advantageous to employ in larger churns two, three, or even more dashers perforated as shown by the drawing.

The operation will be readily understood from the foregoing description.

The parts are few, simple of construction, not liable to get of order, and so arranged that a child may readily operate the churn. It will be observed, too, that the arrangement of mechanism is such that it may be readily connected to the dash-churn in ordinary use, thereby saving to farmers and dairymen the expense of new churns. A short, quick motion is imparted to the dasher, such as has in practice been found most effective for the work to be accomplished. By increasing the width of the frame and platform an additional crank or cranks may be placed on the shaft which operates the balanced lever, and by the employment of additional balanced levers and vertically-reciprocating slides or connecting rods working through the guide-bar, the same mechanism may be made to operate several churns at one and the same time.

What I claim as my invention, and desire to secure by Letters Patent, is—

The employment of the vertically-reciprocating connecting-rod a, working in guide D', in combination with the dash-churn and the balanced lever, arranged and operating in the manner and for the purpose substantially as described.

ORAN W. SEELY.
